SPARK PLUG

Application filed December 27, 1929. Serial No. 416,845.

This invention relates to an improved spark plug for use in connection with internal combustion motors and it has more particular reference to the type of plug embodying a plurality of spark gaps for intensifying the spark and increasing the efficiency of the motor.

In carrying the invention into effect we have evolved and produced a novel arrangement of details cooperating in providing a plug which is characteristic in design, susceptible of easy and accessible cleaning, and otherwise equipped for fulfilling the requirements of a product of this class in a highly satisfactory manner.

In the drawing:

Figure 1 is a view in section and elevation showing one form of the invention.

Figure 2 is a view showing a slightly different form of the invention.

Figure 3 is a bottom plan view of Figure 1.

Figure 4 is a bottom plan view of Figure 2.

In Figures 1 and 3 reference character 5 designates the body of the plug which includes the usual screw-threaded skirt portion 6. In the present instance we provide a retaining plate 7 which is fitted on the lower end of this skirt 6 and holds in place a mica diaphragm 10 which serves to close the chamber 8 to prevent the accumulation of carbon and soot therein.

The lower end portion of the insulator is designated at 9 and it will be observed that this is of tapered configuration, and the bottom thereof rests firmly upon and contacting with the central portion of the mica diaphragm 10 held in place by the ring 7. The electrode is shown as provided with a laterally directed extremity 11, and this is spaced from a contact button 12, the button being arranged for cooperation with the secondary electrode 13. This electrode is shown as provided with a laterally directed end portion 14 spaced from the periphery of the button 12. Thus the end 11 of the main electrode is located on one side and the end 14 of the secondary electrode is located on the diametrically opposite side of the button 12, thus forming two spark gaps operable in an evident manner for intensifying the sparks.

In Figure 2, reference character 15 designates the body and 16 the screw-threaded skirt defining the chamber 17. Here the chamber is closed by a mica diaphragm 18 held in place by a screw-threaded retaining ring 19. The insulator 20 is of cylindrical design and somewhat larger in diameter and bears firmly upon the central portion of the diaphragm and carries the electrode whose end portion is directed laterally as at 21.

The contact button is indicated at 22 and is carried by the mica diaphragm to locate it close to the insulator 20 and in spaced relation from the laterally directed terminal 23 of the secondary contactor electrode 24 which as 65 obvious is mounted on the shell or skirt 16. The principle is the same in that the terminal 21 and terminal 23 form spark gaps on diametrically opposite sides of the disc-like head of the button 22, thereby intensifying the 70 spark in an obvious manner.

Incidentally the terminals 21 and 23 may lie in intimate contact with the underside of the diaphragm or in spaced relation with respect thereto as shown in Figure 1.

A careful consideration of the description in connection with the drawing will enable the reader to obtain a clear understanding of the construction, arrangement, and features. Therefore, a more lengthy description is regarded as unnecessary.

Minor changes in shape, size, and rearrangement of details falling within the scope of the invention claimed may be resorted to in actual practice if desired.

We claim:

A spark plug of the class described comprising a shell, a thin disk of mica having its edges abutting the lower end of the shell, a retaining ring on the lower end of the shell holding the disk in place, a body of non-conducting material carried by the shell and having its lower end contacting the upper face of the disk, a main electrode passing through the body and through a centrally arranged hole in the disk with its end bent at right angles over the outer face of the disk, a ground electrode connected to an inner wall of the shell passing through a hole in the disk and having its outer part bent at 100

right angles over the outer face of the disk, and a button carried by the disk and arranged between and spaced from the extremities of the main and ground electrode to form a pair of spark gaps.

In testimony whereof we affix our signatures.

DAVID C. SMITH.
WALTER P. WALDEN.
